UNITED STATES PATENT OFFICE.

EDSON O. SESSIONS, OF CHICAGO, ILLINOIS, ASSIGNOR TO ALBERT C. BELL, TRUSTEE, OF CHICAGO, ILLINOIS.

INSULATOR MOUNTING.

Application filed June 13, 1919. Serial No. 304,022.

To all whom it may concern:

Be it known that I, EDSON O. SESSIONS, a citizen of the United States, residing at Chicago, in the county of Cook and State 5 of Illinois, have invented a certain new and useful Improvement in Insulator Mountings, of which the following is a specification.

My invention relates to an improved 10 form of insulator mounting by which several insulators may be secured together in a simple manner and at the same time positively, as for example, where it is desired to make use of a plurality of insulators to 15 constitute a combined insulating unit or where it is desired to secure mounting bases to insulators, since my improved construction is readily applicable to either purpose. It is an object of my invention to produce a 20 construction of the kind referred to such that the parts engaging the insulators may readily adapt themselves to any irregularities in the surface of the insulators incident to their manufacture, and yet firmly engage 25 the insulators so that by the use of the device an insulator may be secured firmly to an adjacent insulator or to a mounting plate as desired. Another object of my invention is to provide an insulator mounting of the 30 kind referred to, which shall be easily and inexpensively manufactured.

My invention will best be understood by reference to the accompanying drawings, showing preferred embodiments thereof in 35 which

Fig. 1 shows one form of the mounting devices in sectional view connecting two adjacent insulators.

Fig. 2 shows in a developed plan view the 40 connecting device employed in Fig. 1.

Fig. 3 illustrates the device shown in Fig. 2, bent into circular conformation which is the position it assumes when placed on an insulator.

Fig. 4 shows in a view similar to Fig. 1 a 45 modified construction of the mounting device.

Fig. 5 shows in a view similar to Fig. 3 one of the annular tubes employed as a part 50 of the device shown in Fig. 4.

Fig. 6 is a sectional view of the tube shown in Fig. 5, taken along the line 6—6.

Fig. 7 shows in side elevation a connecting 55 tube employed as a part of the device shown in Fig. 4.

Fig. 8 shows in a view similar to Fig. 4, a modified construction of the device shown in Fig. 4, to adapt said device to the securing of an insulator to a mounting plate, instead of connecting two insulators together. 60

Fig. 9 shows in a view similar to Fig. 4 a second modified form of mounting device, the difference being that the annular tubes shown in Fig. 4 are replaced by ring sections of solid material held in place by set-screws extending through the connecting tube. 65

Fig. 10 shows in a view similar to Fig. 8 the connecting devices of Fig. 9 modified to 70 secure an insulator to a mounting plate instead of connecting two insulators together, as shown in Fig. 9.

Fig. 11 shows in a view similar to Fig. 9 a further modified form of my mounting 75 device for securing a mounting plate to an insulator by means of a short tube which is forced into an engaging position by compressing said tube.

Fig. 12 shows in said elevation a connecting tube employed in the construction shown 80 in Fig. 11 before said tube is compressed.

Fig. 13 shows in cross section the mounting plate shown in Fig. 11 before being secured to the insulator by the connecting tube 85 shown in Fig. 12.

Similar numerals refer to similar parts throughout the several views.

In the construction shown in Figs. 1, 2 and 3, the connecting devices employed consist of a strip of sheet metal 15, which as shown in Fig. 2 has its opposite longitudinal edges rolled over upon the body portion of the strip to form edge beads 16, which may be elliptical or circular in cross section before the device is put in place on the insulator or insulators, these beads extending nearly the entire length of the strip 15, and being cut away at one end of the strip as indicated at 17, so that when the strip is 95 formed to surround the bosses or heads 18 of the insulators 19 to be connected together by the device, the end 17 of the strip 15 overlaps the other end of the strip in which position it is securely held with the beads 16 in the grooves of the insulators adjacent the heads 18 in slightly compressed condition, by welding electrically or otherwise connecting the end 17 to the other end of the strip 15. 100

As a result of this construction the formed 11

strip having its ends secured together as described, securely engages the head of each insulator and the shape of the beads 16 and the spring action of the sheet metal of 5 which the strip 15 is formed, permit the beads to yield and conform to the exact shape of the surfaces of the insulators engaged by them, whether said engaged surfaces are regular or irregular.

- 10 In this manner a series of insulators may be secured together mechanically in a rigid and efficient manner for whatever purpose desired, as for example, for constructing a post insulator consisting of a plurality of 15 individual insulators, for forming a connected series of suspension insulators, or for any other purpose for which it is desired to connect the plurality of insulators to form a single insulating unit. It will be observed 20 that one of the beads 16 may be omitted if desired, and replaced by a mounting plate, secured in any desired manner to the strip 15 either before or after placing the strip on an insulator, so that by this modified 25 construction any desired devices may be securely held in place by the mounting plate on the insulator. This modified construction is not shown in the drawings as the relation between the mounting plate and the 30 strip 15 is of the same nature as that shown and described in connection with Fig. 8 below.

In the construction shown in Fig. 4 the strip 15^a is tubular in form and preferably 35 without a longitudinal joint or seam, being of just the right internal diameter to compress the annular tubes 16^a in place in the grooves adjacent to the heads of the insulators 19^a, when the parts are placed in the 40 connecting position shown in Fig. 4. Each annular tube 16^a is formed of a cross section as indicated in Fig. 6, which may be circular or elliptical, and when the connecting tube 15^a is forced to the position shown in Fig. 4, 45 over the annular tubes 16^a, the latter are flattened somewhat and forced positively into engagement with the adjacent surfaces of the insulation 19^a, whether said surfaces are regular or irregular. The connecting 50 tube 15^a as shown in Fig. 7 is provided along each end with a series of apertures 20, extending through it, which apertures are in line with the annular tubes 16^a when the mounting devices are in connecting position 55 as shown in Fig. 4, and the parts are preferably held in connecting position by electrically welding them together through the apertures 20, or other suitable means.

In the modified construction shown in 60 Fig. 8, the tube 15^b is somewhat shorter than the tube 15^a but of the same general construction, and when in place on the insulator 19^b, is secured to the annular tube 16^b in the manner above described, for the construction 65 shown in Fig. 4. In this construction the

second annular tube 16^a is replaced by a mounting plate 21, which may be secured to the tube 15^b in any suitable manner, as by welding or brazing, either before or after the tube 15^b is placed upon the insulator 19^b, 70 or if preferred, the mounting plate 21 may be an integral part of the tube 15^b.

In the modified construction shown in Fig. 9, the same general result is secured as with the construction of Fig. 4, but in this 75 case the connecting tube 15^a is replaced by a connecting tube 15^c, provided at either end with a plurality of set-screws 22 for engaging the ring sections 16^c, which may be of metal and of a semi-circular or semi-elliptical cross section to fit the grooves adjacent the heads of the insulator 19^c, the outer surfaces of the ring sections 16^c being of conical conformation to prevent the set-screws slipping from the ring section when forces are 85 applied to the insulators tending to separate them. The ring sections may be made in halves or other parts of circles to facilitate placing the sections in position in the insulator. In the modified construction shown 90 in Fig. 10 the connecting tube 15^d is similar to the connecting tube 15^c shown in Fig. 9, and provided with a series of set-screws 22^d for securing the connecting tube to an insulator in the same manner described in connection with Fig. 9, and in this modified construction the other series of set-screws 95 and the other ring sections employed in Fig. 9 are replaced by a mounting plate 23 which, as indicated, may be integral with the connecting ring 15^d, so that any desired devices may be supported upon the mounting plate, and secured to the supporting insulator not shown.

In the modified construction shown in 105 Figs. 11, 12 and 13, a connecting tube 15^e is employed which tube is provided at one end with an inturned flange 24 for engaging the end of a mounting plate 25, the other end of said tube being split at one point, as indicated at 26 in Fig. 12 and provided with an inturned flange 27 to engage the ring sections 16^e fitting the insulator, when the mounting device is in place on the insulator. In constructing the tube 15^e, the split end 110 of said tube is made in expanded conformation, so that the inturned flange 27 may be slipped over the head of the insulator and over the ring sections 16^e, and when the connecting tube is in a position bringing the flange 24 firmly into engagement with the edge of the mounting plate 25, the expanded portion of the connecting tube is 115 compressed by suitable tools, bringing the cut or slit 26 together, in which position it 120 may be held by welding electrically, by brazing or any equivalent means.

If desired, the mounting plate 25 may be constructed as shown in Fig. 13, so that its edge portion 28 extends away from the in-

ner surface of the mounting plate, so that said edge portion is sprung into the plane of the inner surface of the mounting plate, when the connecting tube 15^e is forced to 5 the position shown in Fig. 11 to engage the ring sections 16^e. For this arrangement the 10 spring action for the edge portion of the mounting plate materially assists in rigidly securing the mounting plate to the insulator in desirable position and allows an opportunity for slight irregularities in the dimensions and conformation of the head of the insulator 19^e without interfering with the effectiveness of the mounting device.

15 From the above it will appear that by my invention I have provided a mounting device which may be cheaply constructed, which may be employed to secure a plurality of insulator units together to form a composite insulator, or to secure a mounting plate to an insulator, and that in either case the parts are positively held together in desired relation by the mounting device without danger of injury to the insulator, and 25 without the use of cement.

While I have shown my invention in the particular embodiments above described, I do not, however, limit myself to these exact constructions, as I may employ equivalents 30 thereof, known to the art at the time of the filing of this application without departing from the scope of the appended claims.

What I claim is:

1. In an insulator mounting, the combination of a connecting tube for enclosing the head of an insulator, and an annular member connected with said tube and projecting inwardly from said tube to enter an annular groove adjacent the head of said insulator, 35 said tube being rigid adjacent said annular member, and said annular member being of metal tending to assume a conformation of smaller diameter than the diameter of said groove and comprising an inturned bead formed on one end of said connecting tube.
2. In an insulator mounting, the combination of a connecting tube for enclosing the head of an insulator, and an annular member connected with said tube and projecting 40 inwardly from said tube to enter an annular groove adjacent the head of said insulator, said tube being rigid adjacent said annular member and said annular member being of metal tending to assume a conformation of

smaller diameter than the diameter of said 55 groove and comprising an inturned bead formed on one end of said tube and said connecting tube comprising a strip of metal bent into tubular form with its ends secured together.

3. An insulator mounting comprising an annular tube of sheet spring material having when unrestrained an inner diameter smaller than the diameter of an insulator 60 groove to be engaged thereby, and a metal sleeve carrying said tube at its end portion and preventing expansion of the outer wall of said tube, said tube having a free edge to be contained in said insulator groove permitting expansion of the inner wall of said 70 tube.

4. An insulator mounting comprising a metal sleeve for encircling the head of an insulator having a head and an adjacent groove, and an inwardly extending tubular 75 member at the end of said sleeve and carried thereby and having a semi-circular cross section on its inner surface for engaging the groove of the insulator and a flattened outer surface at its juncture with said sleeve, said 80 sleeve comprising a strip of metal bent into tubular form with its ends secured together.

5. An insulator mounting comprising a metal sleeve for encircling the head of an insulator having a head and an adjacent 85 groove, and an inwardly extending tubular member at the end of said sleeve and carried thereby and having a semi-circular cross-section on its inner surface for engaging the groove of the insulator and a flattened outer 90 surface at its juncture with said sleeve, said tubular member being discontinuous to permit it to yield radially of said sleeve.

6. An insulator mounting comprising a metal sleeve for encircling the head of an 95 insulator having a head and an adjacent groove, and an inwardly extending tubular member at the end of said sleeve and carried thereby and having a semi-circular 100 cross-section on its inner surface for engaging the groove of the insulator and a flattened outer surface at its juncture with said sleeve.

In witness whereof, I have hereunto subscribed my name this 3rd day of June, A. D., 105 1919.

EDSON O. SESSIONS.
